UNITED STATES PATENT OFFICE.

HUGH LAUGHLIN AND EMET BAUMGARDNER, OF EAST PALESTINE, OHIO.

WEIGH-BOX.

SPECIFICATION forming part of Letters Patent No. 284,864, dated September 11, 1883.

Application filed August 1, 1883. (No model.)

To all whom it may concern:

Be it known that we, HUGH LAUGHLIN and EMET BAUMGARDNER, residing at East Palestine, county of Columbiana, and State of Ohio, 5 have made certain new and useful Improvements in Weigh-Boxes; and we do hereby declare the following to be a description of the same, and of the manner of constructing and using the invention, in such full, clear, concise, and exact terms as to enable any person skilled in the art to which it appertains to construct and use the same, reference being had to the annexed drawings, forming a part of the specification, the principle of the invention being herein explained, and the best mode in which we have contemplated applying that principle, so as to distinguish it from other inventions.

The main purpose for which the box is intended is to weigh coal and load it on cars at coal-chutes. Heretofore weighing-boxes have delivered the coal from out their ends. Our box is designed to deliver the coal from its bottom. The object is to adapt the box so that as soon as it is filled with coal and weighed 20 a door in the bottom may be dropped and the coal dumped on the car, said bottom door then returning automatically and immediately into closed position, whereupon the box is ready 25 for a repetition of the above operation. By such a contrivance a single person may attend to the weighing and loading of the coal on the car, and as no strength is required a boy of ten or twelve years can serve as weighing-master. The box may be of any suitable form, 30 preferably oblong, open at the top and upper end for the reception of the coal, and is suspended by suitable means from the scales. Such a contrivance, as will be seen, saves labor, 35 reduces the number of employés usually necessary in weighing and loading coal, and delivers the coal in better condition than in the old form of weighing-boxes.

Referring to the drawings, Figure 1 is a perspective view of the box, at about its normal inclination, as suspended from the scales. The dotted lines show the drop-door open and the gravity-weights correspondingly elevated on the free arms of the levers. Fig. 2 is a reverse plan of the box with the drop-door closed.

A is the box, provided at both longitudinal

ends, respectively, by rods B B', which suspend it from the scales, the two rods B' being about twice the length of the other two rods, B. This gives the box a diagonal inclination 55 in the direction of the drop-door, hereinafter mentioned, for the purpose of facilitating and completing the discharge of the coal. The lower portion of the box has its bottom provided with a drop-door, C, swinging on an 60 axle-rod, a, at its lower end, which axle-rod is safely secured by metallic straps b to the lower end, C', of the box. This axle-rod extends entirely across the end of the box, and adapts the door to swing therefrom downward 65 under a pressure that exceeds the power of the gravity-balls D. These two balls are respectively connected to two levers, E, and are adapted to be secured thereto at any suitable point by means of clamping-screws d. Each 70 lever E is pivoted to one side of the lower end of the box, and has movement in a vertical plane. Each of these levers has connected to its extremity opposite to that provided with a gravity-ball a swinging link, F. The latter has 75 its lower extremity connected to the dropping or free end of the door C. The latches G hold said door in closed position, and are unfastened by the hand-lever H. The weighing-master moves said hand-lever, which in turn loosens 80 the latches, and the door falls. As soon as the coal has been run out of the box the gravity-balls operate through levers E and links F to instantly and automatically raise the door and close it in locked position. The door is then 85 retained closed until the hand-lever again unlatches it. The latches G are of equal size and length, moving in adequate guides e, and sufficiently lap together under the drop-door to receive a connecting-pivot, e', secured by a nut. 90 At this point a small pressure-spring is in contact with their lapped ends to restore them automatically to their normal right line immediately after they have been thrown clear of the catches by the hand-lever. This locks the 95 swinging door again when the gravity-balls D have restored it to its normal position. The upper or dropping edge of the drop-door has also pivoted to it, on each side, a small depending rod, J. These rods work, respectively, 100 freely downward in guides e, and are furnished each at their free ends with a coil-spring, j,

secured from escape by a suitable nut. The design of this is to ease or break the fall of the swinging door C, and so protect the levers E and the connecting parts from damaging strains 5 or shocks.

It will be understood that omissions, substitutions, and changes may be made as regards the forms and parts herein set forth, provided the principle of construction and operation employed in the following claims are retained and

5 We therefore particularly point out and distinctly claim as our invention—

1. A weigh-box formed with a trap-door and 15 provided with mechanism adapted to automatically raise and lock said door after it has discharged the coal, substantially as set forth.

2. In a weigh-box, the combination, with a drop-door formed in the box-bottom, of a swing- 20 ing link having its lower extremity secured to the free end of the door, and a weighted lever fulcrumed to the body of the box and connected to the upper extremity of said link, substantially as set forth.

25 3. In a weigh-box, the combination, with a drop-door formed in the box-bottom and a latch pivoted to the under side of said door, of a catch depending from the side of the box and

adapted to disengage the latch from its catch, substantially as set forth.

30

4. In a weigh-box, the combination, with a drop-door formed in the box-bottom, two latches located on the under side of said door, and having their inner extremities pivoted together, and a spring bearing against said extremities and adapted to automatically lock the latches, of two catches respectively depending from opposite sides of the box, and a hand-lever adapted to engage with one of said latches, and thereby disengage both said latches from 40 their catches, substantially as set forth.

35

5. In a weigh-box, the combination, with a drop-door formed in the box-bottom, of a rod pivoted to the free end of the door, a spring fitted to said rod, and a stop secured to the 45 box-side and adapted to cause said spring to act as a buffer on the drop of the door, substantially as set forth.

In testimony that we claim the foregoing to be our invention we have hereunto set our 50 hands this 16th day of July, A. D. 1833.

HUGH LAUGHLIN.
EMET BAUMGARDNER.
